INVENTOR.

ANTHONY M. BERNARD

BY HIS ATTORNEY,

James F. Williams

UNITED STATES PATENT OFFICE.

ANTHONY M. BERNARD, OF MINNEAPOLIS, MINNESOTA.

READY OPENER FOR GASKET-SEALED CONTAINERS.

Application filed June 24, 1922. Serial No. 570,723.

To all whom it may concern:

Be it known that I, ANTHONY M. BERNARD, a citizen of the United States, residing at Minneapolis, in the county of Hennepin and 5 State of Minnesota, have invented certain new and useful Improvements in Ready Openers for Gasket-Sealed Containers; and I do hereby declare the following to be a full, clear, and exact description of the invention, such as will enable others skilled in 10 the art to which it appertains to make and use the same.

This invention relates to a sealing device for a container of the open top or jar type 15 and especially to a method and means for opening such a sealed container. It is a common practice to seal open-ended jars with a cap comprising a flange disposed at the side of the container and spaced therefrom, a compressible gasket being disposed 20 between said flange and the side of the container for sealing the same. Such a flange is commonly employed with a cover known as the double seal cover which also contacts 25 the top edge of the jar, but the use of such a flange is not limited to such a cover. When it is desired to open the jar it has heretofore been necessary to gouge out a piece of the compressed gasket with some implement in 30 order to get hold thereof. After a hold is secured on the gasket or one of the broken ends thereof the same can be pulled from under the said flange and the cover removed. This gasket removing operation is 35 quite troublesome and difficult, it usually being necessary to place the jar on one side in order to effectively use an implement thereon.

It is an object of this invention, therefore, 40 to provide a method of sealing and sealing means for a jar by the use of which the gasket can be removed with no trouble and little effort.

It is a further object of the invention to provide such a means comprising a strip of 45 flexible material which is placed around the gasket, said strip having a free projecting portion which can be pulled to pull the gasket from under the sealing flange.

These and other objects and advantages 50 of the invention will be fully set forth in the following description made in connection with the accompanying drawings in which like reference characters refer to the same

parts throughout the different views, and in which,

Fig. 1 is a view in side elevation of a sealed jar;

Fig. 2 is a view in vertical section thereof taken on the line 2—2 of Fig. 1, as indicated by the arrows; and

Fig. 3 is a partial similar vertical section on an enlarged scale.

Referring to the drawings, an open ended container or jar 1 is shown having thereon a sealing cover 2. The cover 2 extends across 65 the top edge of the container and contacts therewith to form one seal and is further bent to have a flange 3 depending therefrom and spaced from the exterior of the container. A gasket 4, preferably of continuous 70 annular form is disposed between the flange 3 and the side of the receptacle and compressed by pressing inwardly or crimping in the flange 3. This forms a second seal for the jar. The covers 2 are usually placed in 75 position and pressed or crimped against the gaskets by a machine, although the operation may be performed by hand. In order to provide means for opening the jar a strip of flexible material 5 is used preferably 80 made of thin fabric, which strip is passed around a gasket 4, as shown in Figs. 2 and 3 and has its ends depending at the sides of the receptacle. The strip is placed in position with the gasket and when the flange 3 85 is pressed against the gasket the strip is pressed against the gasket and, being of thin fabric, does not interfere with the sealing operation, the seal being just as tight as if the strip were not used.

When it is desired to remove the cover of the jar, instead of it being necessary to gouge out a portion of the gasket 4 it is only necessary to hold the jar and pull upon the ends of the strip 5, a portion of the gasket 90 is thus pulled from beneath the flange 4 and the gasket can be quickly peeled or drawn from under said flange entirely around the jar. The cover 2 can then be lifted.

From the above description it will be seen 100 that applicant has provided a simple and efficient method of sealing a jar using means by which the sealed gasket can be very easily removed and the cover then lifted. The strip of material merely hangs at one 105 side of the jar while the same is sealed or

while the same is being handled in the trade. If desired, the ends of the fabric can, of course be placed under any label which it may be desired to add to the jar during the 5 commercial handling thereof.

It will, of course, be understood that various changes may be made in the method or in the form, arrangement and material of the apparatus without departing from the 10 scope of applicant's invention, which, generally stated, consists in the matter shown and described and set forth in the appended claims.

What is claimed is:

- 15 1. The method of sealing an open top container comprising positioning a cover thereon having a flange spaced from the exterior of said container, placing a gasket between said flange and said container, placing a strip of thin flexible material transversely around said gasket so as to depend at the side of said container and pressing said flange against said gasket and strip to provide a tight seal.
- 20 2. A seal for an open top container and opener therefor, comprising, a cap having a flange spaced from the side of said container, a gasket compressed between said flange and the container and the strip of thin flexible material passed around said gasket and having a freely extending portion whereby said strip can be pulled to ex-

tract a portion of said gasket from beneath said flange.

3. The method of sealing a jar consisting 35 in placing a cap thereon in contact with an annular gasket and placing a strip of thin flexible material around said gasket, said strip having a freely extending portion which can be pulled upon to remove a portion of said gasket from beneath said cap.

4. A sealing and opening structure for a jar comprising, a cover, a gasket compressed between the same and the exterior of the jar, and a strip of thin flexible material passing 45 transversely around said gasket and having a freely extending portion at the exterior of the jar.

5. A sealing structure for an open top container comprising, a cap inclosing the top 50 of said container and having a flange projecting downwardly at the side thereof, a gasket compressed between said flange and the exterior of said container, and a strip of flexible material passed transversely around said gasket in a plane extending substantially at right angles to the annular plane of said gasket, said strip being compressed with said gasket between said flange and container and adapted to be pulled to draw 55 a portion of said gasket from underneath said flange.

In testimony whereof I affix my signature.

ANTHONY M. BERNARD.
